US00D465619S

(12) **United States Design Patent** (10) Patent No.: **US D465,619 S**
 Weiping (45) Date of Patent: **** Nov. 12, 2002**

(54) **PANEL OF A BIRD CAGE**

(76) Inventor: **Yang Weiping**, Yue Hu Village Henghu Precinct, Fucheng Town, Taishan City, Guangdong (CN)

(**) Term: **14 Years**

(21) Appl. No.: **29/142,067**

(22) Filed: **May 17, 2001**

(51) LOC (7) Cl. **30-02**

(52) U.S. Cl. **D30/116**

(58) Field of Search D30/101-106, D30/108-119; 119/416, 418-420, 428-435, 452-456, 458-472, 474-475, 477, 479, 482, 484-485, 489-491, 500, 502, 512-513, 531, 496-498
